DAVID MANUEL, OF BOSTON, MASSACHUSETTS, ASSIGNOR TO JOHN S. PAINE, OF SAME PLACE.

Letters Patent No. 86,169, dated January 26, 1869.

IMPROVED SPRING-BED BOTTOM.

The Schedule referred to in these Letters Patent and making part of the same.

To all persons to whom these presents may come:

Be it known that I, DAVID MANUEL, of Boston, in the county of Suffolk, and State of Massachusetts, have invented a new and useful Improvement in Spring-Bed Bottoms; and do hereby declare the same to be fully described in the following specification, and represented in the accompanying drawings, of which—

Figure 1 is a top view,

Figure 2, a vertical section, and

Figure 3, a transverse section of a spring-bed bottom, containing my invention.

This invention has reference to one which constitutes the subject of Letters Patent, No. 63,066, dated March 19, A. D., 1867, and granted to myself and Willard Manuel, as assignees of myself, the inventor, my present invention being an improvement in the bed-bottom, and intended not only for holding the springs in place in their prong-holes, but as a supporter of the mattress, or a means of insulating it from the springs.

I have, also, so arranged the spring-groove with respect to the helices, or helix-coils of the springs, as to support them in front as well as in rear, and thereby relieve the prongs from much of the strain to which they are liable when the coils are left unsupported in front.

The drawings represent a bed-bottom, composed of a rectangular supporting or foundation-frame, A, a series of parallel slats, B B B, &c., a series of springs, C C C, &c.

Each of the springs C is a compound one, made usually of a single wire, and in the form as represented in top view in Figure 4, and in side view in Figure 5, and in rear elevation in Figure 6, it having a straight portion, e, at its middle, from each end of which the wire is bent at a right angle; thence each leg is bent in the form of a C-spring, as shown at f; thence in a long curve or side spring c; thence in a helix, as shown at a, and terminates in straight portion or spring g.

There is one of the said springs to each end of each slat, the slat near such end being provided with a notch, h, to receive the part e of the spring.

The two prongs of the spring are inserted in holes made vertically within the cross-bar of the frame, and downward from the groove i, formed in such cross-bar, and running lengthwise of it, such groove being the arc of a circle, in transverse section, so as to receive and fit to the helix-coils of the spring, and extend up both in front and in rear of it. In this way, the groove operates to support the coils of the spring better than if extended up against their back only, as in my former patent. The extra support thus afforded to the coils relieves the prongs from much lateral or other strain, tending to bend them or break them off, or to lift the prongs out of their sockets, as this strain will be resisted by the front part of the groove, the back part

also serving as an abutment to support the coils under back pressure on the spring, and thereby prevent such pressure from bending or breaking the prongs.

The leverage of the springs or weight on them, tends to draw the springs forward, and off their rest, but by having a support in front of and against the coils of each spring, that is, by extending the groove i up in front of the coils, this tendency of the spring to be drawn forward by the slat when weighted will be counteracted.

Instead of employing a cord to go through the coils of the springs of each series, and be fastened at its ends to the frame, as in my patented bed-bottom referred to, (such cord being for the purpose of holding the springs down upon their seats, and preventing them or any of them from falling out of their prong-sockets when the bed-bottom may be turned up or over, as the prongs will generally be loose in their holes or sockets or liable to become so,) I now make use of a cap-bar, k, which extends directly over and upon the helix-coils of the series, and is fastened to the frame A, the whole being as shown in the drawings.

This cap-bar, by its arrangement with the springs and the slats, serves not only as a means of keeping the coils of the springs down upon their seats while the bed-bottom may be in use, or be in the act of being turned up or over, but as a support for a mattress or bed when resting on the slats.

It also so insulates the mattress or bed from the coils of the springs as to prevent wear of the mattress or bed by them.

The cap-bar thus not only performs the functions of the cord above mentioned, but is advantageous in other respects.

I do not herein claim the extension of the spring-supporting frame underneath the springs, and up against the backs of the coils thereof, nor do I claim the employment of a cord to go through the coils of the springs, to keep them in place on the frame.

What I claim as my present improvement or invention may be stated as follows; that is to say—

I claim the arrangement of the cap-bar with the supporting-frame, the slats, and the springs, constructed, arranged, and applied together, substantially as described.

I also claim, in combination with the springs, their supporting-rail or frame, and the slats, the extension of the groove i up, both in front and in rear of and against the helix-coils of each of the springs, as set forth, so as to support the coils both in front and rear of them, as and for the purpose or purposes as described.

DAVID MANUEL.
